United States Patent Office.

GEORGE P. FLOYD, OF QUINCY, MASSACHUSETTS.

Letters Patent No. 77,602, dated May 5, 1868.

IMPROVED RAILROAD-TRACK CLEANER.

The Schedule referred to in these Letters Patent and making part of the same.

Be it known that I, GEORGE P. FLOYD, of Quincy, in the county of Norfolk, and State of Massachusetts, have invented a new and useful Improvement in the Mode of Cleaning Railroad-Tracks by steam, of which the following is a full, clear, and exact description, reference being had to the accompanying drawings, making a part of this specification, in which—

Figure 1 represents a side elevation of a locomotive, showing the application of my invention.

Figure 2 is a sectional view of a nozzle through which the steam is ejected upon the track, and

Figure 3 is an end view of the same.

The nature of my invention consists in a mode of throwing a jet of steam upon the rails of a railroad-track, by means of a nozzle of peculiar construction attached to a pipe, and arranged directly in front of the wheels of a locomotive or car, for the purpose of removing from the rails any snow, ice, oil, grease, or other similar substance calculated to interfere with the gripe of the wheels on the surface of the rails.

It is well known that snow and ice, oil, grease, and substances of a similar character, when placed upon the rails of a railroad-track by any agency, cause the rails to become slippery, so that the wheels of the locomotive will lose their gripe and revolve without advancing.

In some sections of the country, at certain seasons of the year, grasshoppers gather upon the rails in such numbers that the wheels of a locomotive or car passing over them become sufficiently wet and oiled to destroy the friction between the wheels and the rails, and thus impede the progress of the train.

By my invention, it is believed that these obstacles are entirely overcome, and the rails are at once cleared of all obstructions arising from the above-named causes.

Referring to the drawings, A represents a locomotive, which may be of any ordinary construction. D represents a pipe leading from the dome B, or from any other point where steam from the boiler may be conveniently introduced into the same, to a point in front of the wheels of the locomotive, as shown in fig. 1. The

To the outer ends, E, of the pipes D are attached nozzles, K, of the form shown in figs. 2 and 3. The nozzles consist of a mouth-piece, a; and shank, b, which latter is made to screw upon the end of the pipe D, so that it can be removed at pleasure.

The mouth-piece is made with a long and narrow opening, as shown in fig. 3, so as to enable the steam to be thrown on either side of the rail, as well as on the top of the same, for the purpose of removing any snow and ice that might interfere with the flange of the wheel of the locomotive or car.

When it is desired to eject the steam upon the top of the rails only, the outer end of the nozzle may be turned at right angles to its first position, thus exerting the full force of the steam upon the top surface of the rails. The outer end of the nozzle may, however, be so formed as to throw any form or size of jet upon the rails, as may be found desirable.

At the point where the pipes D receive the steam, or at any other suitable point, is arranged a valve, E, to which is attached a rod, J, extending to a point within convenient reach of the engine-driver.

It is obvious that the exhaust steam of the locomotive may be used, instead of steam from the boiler, but as it is necessary that a strong jet of steam should be generally used, it is preferable to conduct it from the boiler.

My invention is equally applicable to clearing the rails of horse or city-railroads, where a boiler can be brought into use.

The pipes D, which conduct the steam to the nozzles K, may be passed into the smoke-stack and coiled, so that the steam may be superheated, if desirable.

I do not claim the employment of steam for cleaning rails of railroad-tracks, but, having thus described my invention,

What I claim as new, and desire to secure by Letters Patent, is—

The nozzles K, attached to the pipes D, when constructed and operating substantially as and for the purpose set forth.

In testimony whereof, I have signed my name to this specification in the presence of two subscribing witnesses.

GEO. P. FLOYD.
